SOUND PRODUCING DEVICE

Raymond R. Rundell, Miami, Fla.

Application August 6, 1945, Serial No. 609,181

4 Claims. (Cl. 84—404)

1

This invention relates to sound producing devices.

An object of this invention is to provide a sound device which may be used as an article of utility, such as a dinner call device, an article of amusement or a toy.

Another object of this invention is to provide a device of this kind embodying a tortuous passage, gongs or other sound elements intersecting the passage, and percussion elements in the form of balls or the like which gravitationally move through the passage and progressively strike the sound elements.

A further object of this invention is to provide a device of this kind wherein the tortuous passage is formed in an invertible housing pivotally carried by a base, so that the passage may be closed at each end and the device operated by gravitation of the percussion element or ball in either position of the housing or direction of travel of the element.

With the foregoing objects in view, and others which may hereinafter more fully appear, I have invented the device shown in the accompanying drawings, which consists of the novel construction, combination and arrangement of parts, as will be more specifically described, and illustrated in the drawings wherein are shown embodiments of the invention, but it is to be understood that changes, variations and modifications may be resorted to which fall within the scope of the invention, as claimed.

In the drawings:

Figure 1 is a detail front elevation partly broken away and in section of a variable sound device constructed according to an embodiment of this invention.

Figure 2 is a detail side elevation partly broken away and in section of the device.

Figure 3 is a sectional view taken on the line 3—3 of Figure 1.

Figure 4 is a detail front elevation of the tortuous passage forming plate used with this device.

Figure 5 is a sectional view taken on the line 5—5 of Figure 1.

Figure 6 is a detailed view of the housing partly broken away and in section showing the sound elements and the mountings therefor.

Figure 7 is a fragmentary sectional view taken on the line 7—7 of Figure 1.

Figure 8 is a detailed side elevation partly in section of a modified form of this invention.

Figure 9 is a detailed front elevation partly broken away and in section with the front plate 55

2

removed of the modification shown in Figure 8, and

Figure 10 is a sectional view taken on the line 10—10 of Figure 9.

Referring to the drawings and first to Figures 1 to 7 inclusive, the numeral 15 designates generally a housing which is formed of upper and lower walls 16 and 17, a rear wall 18 and opposite side walls 19 and 20. The housing 15 is closed at its forward side by means of a transparent wall 21 and a rectangular frame 22 formed with a marginal flange 23 engages the transparent wall or panel 21 and holds this wall or panel against the forward ends or edges of the side and upper and lower walls.

A gong supporting bar or plate 24 is disposed on the inner side of the side wall 19 being spaced inwardly from this side wall by means of spacers 25 and secured to the side wall 19 by fastening devices 26. A plurality of gongs or sound elements 27, 28, 29 and 30 are secured to the bar 24 and extend inwardly therefrom and in the present instance these gongs are in the form of a spiral coil formed of tempered metal, and the 25 gongs are of varying sizes progressing from the smaller gong 27 to the larger gong 30. In this manner variable sounds will be produced when the percussion elements contact with these gongs. A flat gong supporting bar or plate 31 is disposed on the inner side of the side wall 20 being spaced therefrom by spacers 32 and are secured relative to the wall 20 by fastening devices 33. A plurality of gongs or sound elements 34, 35, 36 and 37 are secured to the inner side of the 30 supporting bar 31 and spaced inwardly therefrom.

The sound elements or gongs 34 to 37 are in progressively increased sizes with the smaller size uppermost and arranged in staggered relation with respect to the sound elements 27 to 30 inclusive. In order to provide a means whereby the gongs or sound elements may be progressively actuated, I have provided a tortuous passage forming plate which includes a plate member 38 engaging the forward edges of the supporting 40 bars 24 and 31. The plate 38 is formed with elongated openings 39, 40, 41 and 42 through which the gongs 27 to 30 are adapted to loosely project, as shown more clearly in Figure 3. The plate 38 is also formed with a second series of 45 elongated openings 43, 44, 45 and 46 at the opposite lengthwise vertical edge of the plate and through which the gongs 34 to 37 are adapted to loosely project. A tortuous passage is formed on the forward side of the plate 38 by means of a series of spaced apart parallel flanges or walls 46

and 47, the flanges 46 and 47 at one end of the tortuous passage being closed by a connecting wall 48.

The tortuous passage, generally designated as 49, is of zig-zag configuration with successive oppositely inclined portions and this passage is broken at the point where the gongs project through the elongated openings of the plate 38, the projecting portions of the gongs forming closures for the adjacent opposite ends of the oppositely inclined portions or sections of the passage 49 so as to be disposed across or to intersect the lower ends of the oppositely inclined portions of said passage or junction points thereof. A ball or percussion member 50 is mounted in the passage 49 and is adapted to gravitationally move downwardly through this passage, first striking the uppermost of the gongs, which in Figure 1 is the gong 34. The ball or percussion member 50 then moves in the opposite direction and strikes the uppermost gong 27 and then in alternate opposite directions in the succeeding oppositely inclined portions to strike the remaining differently sounding gongs 35, 28, 36, 29, 37 and 30 in the order stated and to strike the same in the reverse order upon the housing and passage being inverted or reversed in position. When the ball 50 reaches the lower end of the tortuous passage 49 the ball will engage against a lower connecting wall 51, which closes the lower end of the tortuous passage.

The walls 46 and 47 forming the tortuous passage are secured to the plate 38 by striking lugs 52 and 53 from the inner edges of the walls 46 and 47 respectively, and these lugs are then extended through slots 54 and 55 in the plate 38 and bent at right angles on the inner or rear side of the plate 38. The housing 15 is pivotally mounted on a supporting base which includes a pair of uprights 56 and 57 carried by a base 58. The upright 56 is formed with a pivot member 59 which is adapted to engage in a detent 60 formed in the side wall 19. The upright 57 is also formed with a pivot member 61 engageable in a detent 62 formed in the wall 20.

Referring now to Figures 8, 9 and 10, there is disclosed a modified form of this invention wherein the tortuous passage 63 for the percussion member 64 is formed in a block 65. A plurality of bells or sound elements 66, 67, 68, 69, 70 and 71 are secured to the block 65 by fastening devices 72, as shown in Figure 10. In the present instance the sound elements 66 to 71 are in the form of bells and in order that the vibrations of the bells 66 may pass out of the block 60 and the tortuous passage 63, openings in the form of slots 73 are provided in the block 65 adjacent each sound element. A transparent cover plate 74 is secured by fastening devices 75 to the forward side of the block 65 and the block 65 is pivotally supported on a pair of spaced uprights 76 which are carried by a base plate 77. The uprights 76 have pivot members 78 on the inner sides thereof which engage in detents or recesses 79 formed in the adjacent or side edges of the block 65.

In the use and operation of this device the two forms of the invention will operate in the same manner. A single percussion member or ball is preferably disposed in the tortuous passage and the housing, as for example housing 15, is disposed in an upright position with the ball 50 at the upper end of the tortuous passage 49. The ball 50 will roll downwardly in the tortuous passage 49 striking the gongs or

sound elements in succession until the ball reaches the lower end of the tortuous passage. The ball may be returned to the upper end of the tortuous passage by merely inverting the housing 15 and upon inverting of the housing 15, the ball will roll downwardly through the tortuous passage striking the deeper toned sound elements first and finally striking the higher toned or pitched sound elements which are the smaller elements 27 and 34. The housing 15 may be reversed as often as may be desired and it will be understood that this device may be used as a dinner gong or dinner call or may be used as a sounding toy for children and may be used as an element of musical education with the sound elements having predetermined pitches related to musical instruments.

What I claim is:

1. A sound device comprising a housing formed of parallel side walls, a rear wall, a pair of inner plates parallel with said side walls, means securing said inner plates to said side walls, spaced sound elements carried by said inner plates, a slotted plate parallel with said rear wall and abutting against the forward edges of said pair of plates, forwardly projecting marginal flanges carried by said slotted plate, said elements projecting through the slots, tortuous passage forming means fixed to the outer side of said slotted plate, said passage being closed at the opposite ends thereof, a transparent front wall carried by said housing forming the front wall of said passage, and a ball loosely disposed in said passage for movement along the passage in opposite directions to strike the elements in reverse order when the housing is disposed in inverted positions.
2. A sound device comprising a housing formed of parallel side walls, a rear wall, a pair of inner plates parallel with said side walls, means securing said inner plates to said side walls, spaced sound elements carried by said inner plates, a slotted plate parallel with said rear wall and abutting against the forward edges of said pair of plates, forwardly projecting marginal flanges carried by said slotted plate, said elements projecting through the slots, tortuous passage forming means fixed to the outer side of said slotted plate, said passage being closed at the opposite ends thereof, a transparent front wall carried by said housing forming the front wall of said passage, a ball loosely disposed in said passage to successively strike said sound elements upon movement along the passage, and means pivotally supporting said housing whereby said housing may be reversed to cause movement of the ball along the passage in an opposite direction to cause reverse striking of the sound elements thereby.
3. A sound device comprising a housing formed of parallel side walls, a rear wall, a pair of inner plates parallel with said side walls, means securing said inner plates to said side walls, spaced sound elements carried by said inner plates, a slotted plate parallel with said rear wall and abutting against the forward edges of said pair of plates, forwardly projecting marginal flanges carried by said slotted plate, said elements projecting through the slots, tortuous passage forming means fixed to the outer side of said slotted plate, said passage being closed at the opposite ends thereof, a transparent front wall carried by said housing forming the front wall of said passage, a ball loosely disposed in said passage, and a U-shaped base pivotally supporting said

housing whereby said housing may be inverted to cause travel of the ball in opposite directions in the passage to strike the elements successively in reverse order.

4. A sound device comprising a rectangular housing having front and rear walls, a slotted plate in said housing spaced from, and parallel to, said front and rear walls, spaced sound elements mounted behind said plate and projecting forwardly through the slots formed therein, tortuous passage forming means fixed to the front side of said plate, said passage being closed at the opposite ends thereof with said housing front wall forming the front wall thereof, and a ball loosely disposed in said passage for movement 15

therewith in opposite directions to strike said sound elements in reverse order when the housing is disposed in inverted positions.
